(57) CLAIM

The ornamental design for a cosmetic beauty station, as shown and described.

DESCRIPTION

FIG. 1 illustrates a perspective view of an exemplary embodiment of a cosmetic beauty station.

FIG. 2 illustrates a front view of the cosmetic beauty station of FIG. 1.

FIG. 3 illustrates a rear view of the cosmetic beauty station of FIG. 1.

FIG. 4 illustrates a left side view of the cosmetic beauty station of FIG. 1.

FIG. 5 illustrates a right side view of the cosmetic beauty station of FIG. 1.

FIG. 6 illustrates a top view of the cosmetic beauty station of FIG. 1; and,

FIG. 7 illustrates a bottom view of the cosmetic beauty station of FIG. 1.

The broken lines show portions of the cosmetic beauty station which form no part of the claimed design.
